RAIL BENDER.

Dale A. Benner, Alton, Ill.

Application May 17, 1943, Serial No. 487,304.

2 Claims.

(Cl. 153—38)

This invention relates to rail benders of the type used for bending or straightening railway rails and other elongated metallic articles in conformity with the desired curvature of the track to be provided by the rails, or the desired curvature of the other articles.

Objects of the invention are to provide an improved portable metallic frame composed of a minimum amount of material and of minimum weight, and having its parts and structural elements in novel cooperative assembly and formation in order to resist and withstand, without deformation, the severe and sometimes excessive pressures, strains and stresses to which it is subjected when in use; to provide an elongated tubular socket integral with and in the frame midway between its ends for receiving the outer end portion of the threaded shaft which is operative to apply pressure against the rail or other article midway between the ends of the frame in order to bend said rail or article; and to embody in the frame novel means for optionally and interchangeably supporting different types of mechanism for operating and moving the shaft longitudinally to apply pressure against and bend the rail or other article engaged with said frame.

Another object of the invention is to provide an improved portable metallic rail bender frame composed of a minimum amount of material and possessing maximum strength, and means in and forming an integral part of said frame for optionally and interchangeably supporting different types of operating mechanism for the screw-threaded bender shaft and for preventing deformation of the frame.

This invention relates more specifically to that type of portable metallic rail benders disclosed in my prior Patents No. 2,261,949, November 11, 1941, and No. 2,269,752, January 13, 1942. The portable metallic frames disclosed by said patents differ from each other in indispensable features of construction in order to cooperate with the types of shaft operating mechanism disclosed in said respective patents. That is, said Patent No. 2,261,949 discloses an operating mechanism for the screwthreaded shaft, comprising a nut mounted in the frame, and an oscillating ratchet mechanism pivotally supported about the nut for turning the nut on and about the shaft in order to move the shaft longitudinally during operation of said operating mechanism. The frame of said Patent No. 2,261,949 differs substantially and in indispensable features from the frame disclosed in said Patent No. 2,269,752 in particulars making it impracticable or impossible to interchange or

use the oscillating ratchet nut operating mechanism in both frames optionally. And Patent No. 2,269,752 discloses a frame adapted for a nut of particular form and rotative to move the shaft longitudinally, and said nut cannot be interchanged and substituted for the ratchet operated nut of Patent No. 2,261,949 in the frame of said last named patent. The frames of said respective patents sometimes became deformed under the excessive pressures, strains and stresses to which they were subjected when in use.

Additional objects and advantages of the present invention should be apparent from the following description, reference being made to the annexed drawings, in which—

Fig. 1 is a side elevation showing my improved rail bender frame having a ratchet shaft operating mechanism mounted therein.

Fig. 2 is an enlarged cross-sectional view on the line 2—2 of Fig. 1.

Fig. 3 is a similarly enlarged sectional view on the line 3—3 of Fig. 1.

Fig. 4 is an elevation showing the opposite side of my improved rail bender frame from that of Fig. 1 and having a flanged nut device therein for operating the bender shaft.

Fig. 5 is an enlarged sectional view on the line 5—5 of Fig. 4.

Fig. 6 is a similarly enlarged sectional view on the line 6—6 of Fig. 4.

Fig. 7 is a cross-sectional view on the line 7—7 of Fig. 1, looking in the direction of the arrows.

The metallic frame of my improved portable rail bender is a unitary or one-piece element having all of its parts and structural features integrally united, thus avoiding the use of brazed or welded connections or joints. That is, the frame is preferably composed of a single casting, with the exception that the handle may, if desired, be attached to the frame after the frame and handle have been separately formed.

As shown, the portable metallic frame is composed of an outer angular or bowed tension member 1, an inner angular or bowed compression member 2, and hooks 3 formed integral with the ends of said compression members and projecting therefrom in parallel relationship to engage the rail or article 4 that is to be bent or straightened; two spaced inwardly converging combined compression members and tension arms 5 extending from integral connection with the tension member 1 to integral connection with diametrically opposite portions of the periphery of a combined abutment and guard ring 6; two spaced parallel compression members 7 integrally connecting the

inner compression member 2 with the respective converging arms 5 at points between and substantially spaced from both the outer tension member 1 and the ring 6; a tubular socket 8 integrally connecting the member 1 and the ring 6 and having open outer and inner ends; flanges 9 integral with diametrically opposite sides of the socket 8 and extending to integral connection with the member 1 and ring 6, respectively, about midway between the connection of the arms 5 with said member 1 and ring 6; and an additional compression member 10 integral with and projecting inwardly from the inner compression member 2 at each side of the central hole 11 which is in alignment with the opening through the socket 8. These additional compression members 10 have their adjacent ends at diametrically opposite sides of the hole 11 and extend outwardly along the inner compression member 2 across the ends of the two parallel compression members 7 to offset webs 12 integrally connecting the outer end portions of the compression members 2 with the hooks 3.

The aligned hooks 3 open at the same side of the frame which includes the parts arranged in the definite cooperative relationship above described and which I have found resist and withstand the severe and excessive pressures, strains and stresses to which the frame is subjected when the rail bender is in use, and prevent deformation of the frame. The compression members 2 converge inwardly and upwardly from integral connection with the lower portions of the bodies of the hooks 3. In my improved frame, the lower portions of the angular spaces between the compression members 2 and the bodies of the respective hooks 3 are closed by the said offset webs 12 formed integral with said parts. Above and laterally offset from the webs 12 there are webs 13 extending along the inner surfaces of the tension member 1, compression member 2, converging arms 5, parallel compression members 7, and hooks 3, within the spaces bordered by said parts. The webs 13 are about midway between the side edges of the tension member 1 and the compression member 2 and are offset laterally from the webs 12 toward the open side of the hooks 3. The adjacent edges of the webs 12 and 13 are integrally connected to provide maximum strength with a minimum of metal at these points. Openings 14 through the webs 13 reduce the amount of metal that would otherwise be required without substantially diminishing the strength of the novel frame structure.

The webs 15 are formed integral with the inner or adjacent surfaces of the parallel compression members 7 and extend continuously from the inner compression member 2 to and along the inwardly converging arms 5 above and outwardly from the ring 6. Thus, an enlarged central opening 16 in the frame is formed between the inner compression member 2, the ring 6, and the webs 15. Said opening 16 is designed and adapted to receive and contain the operating mechanism for the threaded bender shaft 17 which extends through the hole 11 in the compression member 2, across the central opening 16, and into the tubular socket 8 for longitudinal movements. The triangular spaces defined by the tension member 1, the inwardly converging arms 5, and the tubular socket 8, are preferably filled by webs 18 formed integral with said parts and in the same plane with the webs 13 and 15.

This frame is provided with these parts ar-

ranged in the relationship shown and described and cooperating to provide a frame composed of a minimum amount of metal and possessing maximum strength, in order to permit interchange and substitution of the operating mechanism shown in Figs. 1, 2 and 3, for the operating mechanism shown in Figs. 4, 5 and 6, and vice versa.

The mechanism shown in Figs. 1, 2 and 3 for moving the shaft 17 longitudinally in opposite directions comprises a ratchet nut 19 screwed on the bender shaft 17 and, when in position for use, is located in the central opening 16 with its inner end seated and rotative against the inner compression member 2. The two additional compression members 10 extend almost to the central hole 11 and are separated from the ratchet nut 19 only by the compression member 2 against which the said nut 19 directly bears. A ring 20 has a radial flange 21 extending inwardly from its inner end, which seats directly against the outer end of the nut 19 and encircles an outwardly extended tubular portion 22 of the nut. The wall of the opening through the nut 19 and the tubular extension 22 are formed with threads (Fig. 2) screwed on the threaded shaft 17. A ring 23 having approximately the same internal diameter as the ring 20 abuts against the outer end of said ring 20 and has a radial outer end wall 24 abutting against the ring 6 and having a central opening receiving the tubular portion 22 of the nut 19 and being thereby held from lateral displacement and disalignment.

A roller anti-friction bearing unit comprising duplicate race rings 25, an annular series of tapered rollers 26 located between and radially of the axis of said rings 25 and of the nut extension 22, and a retaining ring 27 encircling the rings 25 and the series of rollers 26, is mounted within the annular space formed around the tubular portion 22 and enclosed by the rings 20 and 23, the flange 21 of the ring 20, and the end wall 24 of the ring 23. One of the race rings 25 seats against the flange 21, and the other race ring 25 seats against the end wall 24 which bears against the combined abutment and guard ring 6. The ring 20 is directly attached to the ratchet nut 19 by a number of fastener pins 28 extending through holes in the flange 21 of said ring and engaging in holes in the outer end of said nut 19, leaving the ring 23—24 free to remain stationary or to rotate with the ring 20—21 when the nut 19 is rotated.

Thus, the nut 19 may be rotated by rotating the ring 20 which constitutes a handle or hand wheel for such purpose. And the nut 19 may be rotated by the ratchet mechanism shown, comprising a ring 29 encircling the ratchet nut 19 for oscillating movements about the axis of said nut and supporting a reversible ratchet 30 engageable with the peripheral teeth 31 to turn said nut forcibly in either direction. The ring 29 is formed with a socket 32 which is adapted to receive an end of an operating lever or bar for turning the operating mechanism in either direction to move the shaft 15 longitudinally in one direction or the other, as desired. The ring 29 and the reversible ratchet 30 are of the same construction and mode of operation as disclosed in my prior Patent No. 2,261,949. The ratchet ring 29 is prevented from longitudinal displacement along the nut 19 by the compression member 2 and the ring 20 between which said ratchet ring is located when this mechanism is assembled in the frame.

In this mechanism, the anti-friction bearing

unit consisting of the race rings 25, rollers 26, and retaining ring 27 are completely enclosed by the rings 20 and 23. In this manner, it is practically impossible for dirt and other foreign particles to enter and foul the anti-friction bearing. The inner end of the bender shaft 17 is provided with a rigid head 33 for engagement against the rail 34 or other article mounted on the hooks 3 for bending or distortion by operation of said shaft and holds the shaft from turning with the nut 19.

The operating mechanism shown in Figs. 4, 5 and 6 is optionally and interchangeably used in the improved frame herein disclosed. That is, the operating mechanism above specifically described and shown in Figs. 1, 2 and 3, or the operating mechanism shown in Figs. 4, 5 and 6, may be used optionally and interchangeably in the same frame. The interchangeable operating mechanism shown in Figs. 4, 5 and 6 comprises a nut 35 having its inner end arranged to bear and seat against the compression member 2 and having on its outer end a tubular extension 36. When the nut 35 is in position for use in the frame, the compression members 10 which extend almost to the hole 11 are separated from said nut only by the compression member 2 which constitutes a seat for said nut. The walls of the opening through the nut 35 and extension 36 are threaded. To assemble the device for use, the nut unit 35-36 having the bearing device connected therewith as shown are placed in the central opening 16, and the shaft 17 is extended through the hole 11 and screwed outwardly through the nut. The device may be disassembled by screwing the shaft 17 inwardly until it is disconnected from the nut. The other form of the device is similarly assembled and disassembled, the nut unit 19-22 with the bearing and ratchet devices being placed in the opening 16 for attachment to the shaft 17. The outer end of the nut 35 is formed with an integral cylindrical wall 37 coaxial with the tubular extension 36 and cooperating therewith to form an annular space 38. An anti-friction roller bearing, precisely like and interchangeable with the anti-friction roller bearing already described and interchangeable therewith and having the same reference numerals applied to like parts, is mounted in the annular space 38. One of the bearing rings 25 seats against the end wall of the nut 35 and the other ring 25 seats against the combined abutment and guard ring 6. The end of the cylindrical wall 37 is very close to or engages the ring 6 and functions to guard the anti-friction bearing and prevent practically all foreign substances from entering and fouling said bearing. The end of the tubular extension 36 is also close to or nearly against the ring 6, so that it is impossible for any appreciable amount of foreign substances to enter the anti-friction bearing through the socket 8. The nut 35 is formed with a series of integral circumferentially spaced radial flanges 39, each of which has a hole 40 to receive and wholly support one end of an insertable and withdrawable operating lever for said nut. A handle 41 is formed integral with the outer tension member 1 at opposite sides of the socket 8.

From the foregoing, it is evident that my improved portable metallic frame is composed of a minimum amount of metal and is of minimum weight. The structural parts and elements of the frame are arranged in a novel cooperative relationship in order to resist and withstand the severe and sometimes excessive pressures, strains and stresses to which the device is subjected when

in use, without deformation. The inner compression member 2 constitutes a direct abutment for the inner end of the ratchet nut 19 of the operating mechanism shown in Figs. 1, 2 and 3; and also for the inner end of the nut 35 of the operating mechanism shown in Figs. 4, 5 and 6. In both instances, the additional compression members 10 of the unitary portable frame support and strengthen the central portion of the compression member 2 and cooperate therewith and with the remaining elements of the frame to prevent distortion or deformation under the severe or excessive pressures, strains and stresses which the device must resist. The frame of this construction permits optional and interchangeable use of the operating mechanisms both of which have parts cooperating directly with the combined abutment and guard ring 6 of the frame to prevent foreign substances from entering and becoming lodged in and fouling the anti-friction bearing. The operating mechanisms accommodate the same anti-friction bearing optionally and interchangeably.

It is also evident that this invention attains all of its intended objects and purposes efficiently, economically, and satisfactorily, and possesses many advantages over other devices intended for the same uses and which cannot use or embody different types of operating mechanisms for the same rail bender shaft.

I claim:

1. In a portable rail bender, a one-piece metallic frame comprising spaced inner and outer members having hooks integrally connecting their outer ends, said inner member having a central hole midway between said hooks, a tubular socket integral with said outer member in alinement with said hole and separated from said inner member by a space, inwardly converging compression members integrally connecting said outer member with the inner end of said socket, a pair of compression members integrally connecting said inner member and said converging compression members at opposite sides of said space and said hole, web elements extending along the sides of said arms and said compression members and integrally connecting said inner and outer members with each other and also integrally connecting all of said compression members with said inner and outer members, a threaded shaft extending through said hole and outwardly across said space and into said socket, operating mechanism for said shaft mounted in said space between said tubular socket and said inner member, and two compression members integral with the inner side of said inner member extending longitudinally thereof toward said hooks and having their inner ends between and inwardly substantially beyond said pair of compression members and adjacent to opposite sides of said hole for cooperating with said inner member and pair of compression members to support said operating mechanism and prevent distortion of said frame, and an anti-friction thrust bearing between said mechanism and said socket and overlying substantial portions of the inner ends of said last named compression members.

2. In a portable rail bender, a metallic frame comprising spaced bowed inner and outer members having hooks integrally connecting their outer ends, said inner member having a central hole midway between said hooks, a tubular socket integral with said outer member in alinement with said hole and having its inner end separated from said inner member by a space, an outwardly

extended radial abutment integral with the inner end of said socket, a pair of compression members integrally connecting said inner and outer members at opposite sides of said hole and said socket and also having integral connection with said abutment, a threaded shaft extending through said hole and outwardly across said space and into said socket, two compression members integral with the inner side of said inner

member extending longitudinally thereof between said hooks and said hole and having their inner ends located closer to opposite sides of said hole than are said pair of compression members, and 5 operating mechanism for said shaft mounted between said inner member and said abutment and overlying substantial portions of the inner ends of said last named compression members.

DALE A. BENNER.
